ROAD MATERIAL MIXER

James H. Bell, Maxwell, Calif.

Application January 7, 1941, Serial No. 373,423

4 Claims. (Cl. 94—44)

This invention relates to road making equipment and particularly to apparatus for mixing the materials, including oil, with which many secondary highways are surfaced.

The principal object of my invention is to provide a traveling machine for the purpose by means of which the materials will be thoroughly mixed with a single traversal of the machine along the stretch of road being treated.

A further object is to provide a machine for the purpose, the material engaging and mixing members of which may be individually adjusted vertically as conditions may render advisable for the best results.

A further object of the invention is to produce a simple and inexpensive device and yet one which will be exceedingly effective for the purpose for which it is designed.

These objects I accomplish by means of such structure and relative arrangement of parts as will fully appear by a perusal of the following specifications and claims.

In the drawings similar characters of reference indicate corresponding parts in the several views:

Figure 1 is a top plan view of the machine.

Figure 2 is a side elevation thereof.

Figure 3 is a longitudinal section on line 3—3 of Fig. 1.

Referring now more particularly to the characters of reference on the drawings, the machine comprises side wall members or plates which as here shown are built up of sheet metal plates 1, smooth on their inner adjacent faces, and reinforced about their periphery on the outside by longitudinal angle irons or similar members 2, the lower longitudinal one of which forms ground engaging shoes or runners. The side walls are rigidly connected across the top at intervals by crossbeams 3, supported by which are longitudinal beams 4. The above described structure forms the frame and road-material confining unit of the machine, and is provided at its forward end with a draft yoke 5 adapted for connection to a tractor or the like.

Extending laterally from one plate 1 toward but terminating short of the other plate are mixing augers 6, spaced apart lengthwise of the plate. Extending from the other plate 1 toward but terminating short of said one plate are other mixing augers 7. These are disposed in planes centrally between augers 6, augers 6 and 7 overlapping each other somewhat. Augers 6 are connected together for simultaneous rotation at the same speed by suitable means such as a chain drive 8 on the outside of corresponding plate 1,

while augers 7 are similarly connected by a chain drive 9 on the outside of the other plate 1.

Both chain drives are connected by suitable means so as to be simultaneously driven in such direction that the sets of augers 6 and 7 will both act to advance material engaged thereby toward the area centrally between side plates 1. In the present instance, such means is shown as comprising other chain drives 10 connected to drives 8 and 9 at their forward end and mounted on separate but aligned shafts 11 mounted on the front crossbeam 3. Bevel pinions 12 are mounted on shafts 11 at their adjacent ends, which are engaged by a bevel gear 13. This gear may be driven from the power take-off shaft of the draft tractor if desired, but as here shown, the drive means for said gear comprises an internal combustion engine 14 supported from the longitudinal beams 4.

Each auger is provided with end bearings 15 mounted for vertical adjustment on uprights 16 on the corresponding side wall members and uprights 17 depending from and rigid with beams 4 behind the axis of the corresponding augers.

25 In this manner, the augers may be adjusted from positions close to the normal road level as shown to various higher position, as operating or mixing conditions may demand for the most effective action. In order to maintain chain drives 8 and 10 taut with any such adjustment of the front augers, to which the rear end of these chain drives are connected, spring pressed idlers 18 are mounted on the side walls to engage one run of the chains of said drives as shown in Fig. 2.

Immediately behind each auger, a vertical plate 19 is mounted, forming a back stop for the adjacent portion of the road material being acted on by the corresponding auger. These plates are parallel to the augers, and while of sufficient length to overlap each other, are somewhat shorter than the augers as clearly shown in Fig. 1. Plates 19 also are mounted for vertical adjustment from positions adjacent the ground or the bottom level of the side wall members by suitable means. As here shown, such means comprises uprights 20 on and behind the plates, cooperating with fixed uprights 21 and 22 on the side members and depending from beams 4 respectively; the plate uprights being adjustably bolted to the fixed uprights as shown at 23.

In operation, the side wall members normally rest on the road, being dragged along by the draft vehicle and with the windrow or layer of material to be mixed in line with the foremost augers. The foremost auger, which with the others is being

rotated at a considerable speed, engages the material, churning it about and mixing it, while advancing it transversely and finally discharging it in the path of the next opposed auger. This auger in turn engages the material, further mixing it, and also advancing it transversely and into the path of the next opposed auger behind. This action continues with each auger until the material, in a thoroughly mixed condition, is left behind the machine in the form of a windrow ready to be acted on by a grader or spreader following behind.

It will be noted that by reason of the fact that alternate augers terminate at their laterally inner ends short of the opposite side wall and overlap only for a minor portion of their length, and that adjacent augers which project from the same side wall are spaced apart a substantial distance lengthwise of the implement, an unobstructed material-receiving chamber C of substantial size both transversely and longitudinally of the implement is formed between said adjacent augers and beyond the laterally inner end of the alternate and intermediate auger. These chambers are advantageous in that they permit the material from each auger to discharge freely, and into the path of a substantial portion of the length of following alternate auger whereby a relatively great mixing capacity is accomplished without overloading or back pressure on the augers.

In order to facilitate transportation of the machine, as well as to enable it to be tilted to one side or the other of the road if necessary, I provide a pair of wheels 24. These are disposed laterally out from the side wall members in positions lengthwise thereof to substantially balance the weight of the machine. The wheels are mounted on the lower end of arms 25 which are pivoted at their upper end on the side wall members as at 26. Individual means is provided for each arm to rotate the same to alter the level of the corresponding wheel relative to the machine, and to hold the arm in such adjusted position. Various devices may be employed for the purpose, as for instance a screw shaft 27 swivelly mounted on the adjacent side wall member and threaded through a thimble on an auxiliary arm 28 rigid with arm 25.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a road material mixer which includes a frame structure having a pair of spaced sidewalls connected together for movement along a road with the material to be mixed confined therebetween, and a plurality of driven mixing augers supported at one end at and projecting laterally inward from the sidewalls; said augers projecting from the sidewalls in alternate relation and terminating at their laterally inner ends a substantial distance short of the opposite sidewall, alternate augers overlapping at said laterally inner ends for only a minor portion of their length and adjacent augers projecting from the same

sidewall being spaced a substantial distance lengthwise of the frame structure, whereby material receiving chambers of substantial size, both transversely and longitudinally, are formed between said adjacent augers and beyond the discharge end of the alternate and intermediate auger, and means included in the frame structure supporting said augers at said laterally inner ends independently of said opposite sidewall and clear of said chambers.

2. In a road material mixer which includes a frame structure having a pair of spaced sidewalls connected together for movement along a road with the material to be mixed confined therebetween, and a plurality of driven mixing augers supported at one end at and projecting laterally inward from the sidewalls; said augers projecting from the sidewalls in alternate relation and terminating at their laterally inner ends a substantial distance short of the opposite sidewall, alternate augers overlapping at said laterally inner ends for only a minor portion of their length, alternate strike-off boards projecting from the sidewalls behind but adjacent the augers, alternate boards overlapping at their laterally inner ends but terminating short of the corresponding ends of the augers, and adjacent augers and boards which project from the same sidewall being spaced apart a substantial distance lengthwise of the frame structure, whereby material receiving chambers of substantial size, both transversely and longitudinally, are formed between said adjacent augers and boards, and beyond the discharge end of the alternate and intermediate auger, and means included in the frame structure supporting said augers at said laterally inner ends, and said strike-off boards intermediate their ends, independently of the opposite sidewall and clear of said chambers.

3. In a road material mixer which includes a frame structure having a pair of spaced sidewalls connected together for movement along a road with the material to be mixed confined therebetween, and a plurality of driven mixing augers supported at one end at and projecting laterally inward from the sidewalls; said augers projecting from the sidewalls in alternate relation and terminating at their laterally inner ends a substantial distance short of the opposite sidewall, alternate augers overlapping at said laterally inner ends for only a minor portion of their length and adjacent augers projecting from the same sidewall being spaced a substantial distance lengthwise of the frame structure, whereby material receiving chambers of substantial size, both transversely and longitudinally, are formed between said adjacent augers and beyond the discharge end of the alternate and intermediate auger, and means included in the frame structure supporting said augers at said laterally inner ends independently of said opposite sidewall and clear of said chambers; said means comprising a pair of transversely spaced longitudinal beams disposed horizontally above the augers, one of said beams being in substantially the vertical plane of the laterally inner ends of the augers projecting from one sidewall, the other beam being in substantially the vertical plane of the laterally inner ends of the augers projecting from the opposite sidewall, and uprights connected between said beams and the corresponding laterally inner ends of said augers in supporting relation to the latter.

4. In a road material mixer which includes a frame structure having a pair of spaced sidewalls

connected together for movement along a road with the material to be mixed confined therebetween, and a plurality of driven mixing augers supported at one end at and projecting laterally inward from the sidewalls; said augers projecting from said sidewalls in alternate relation and terminating at their laterally inner ends a substantial distance short of the opposite sidewall, alternate augers overlapping at said laterally inner ends for only a minor portion of their length, alternate strike-off boards projecting from the sidewalls behind but adjacent the augers, alternate boards overlapping at their laterally inner ends but terminating short of the corresponding ends of the augers, and adjacent augers and boards which project from the same sidewall being spaced apart a substantial distance lengthwise of the frame structure, whereby material receiving chambers of substantial size, both transversely and longitudinally, are formed between said adjacent augers and boards, and beyond the discharge end of the alternate and intermediate

auger, and means included in the frame structure supporting said augers at said laterally inner ends, and said strike-off boards intermediate their ends, independently of the opposite sidewall and clear of said chambers; said means comprising a pair of transversely spaced longitudinal beams disposed horizontally above the augers, one of said beams being in substantially the vertical plane of the laterally inner ends of the augers projecting from one sidewall, the other beam being in substantially the vertical plane of the laterally inner ends of the augers projecting from the other sidewall, uprights connected between said beams and the corresponding laterally inner ends of said augers in supporting relation to the latter, and other uprights connected between the beams and said strike-off boards intermediate the ends of and in supporting relation to the latter, adjacent augers and strike-off boards being supported from different ones of said beams.

JAMES H. BELL.
